UNITED STATES PATENT OFFICE.

CHARLES P. ROBSON, OF LANSDOWNE, PENNSYLVANIA.

OVEN LIGHT.

Application filed June 12, 1924. Serial No. 719,493.

The principal objects of the present invention are, first, to provide for easily and conveniently turning the device to admit light to the oven and to close the opening through which the light is admitted to prevent escape of vapors and the like from the oven and to protect the lamp or light; second, to facilitate the use of either gas or electricity; and third, to simplify and improve both the construction and operation of the oven lamp.

Other objects of the invention will appear from the following description which will be given in connection with the accompanying drawings and finally the invention will be claimed.

In the accompanying drawings—

Figure 1 is an elevational view of the light as seen from the front of the oven.

Fig. 2 is a sectional view taken on the line 2—2 of Fig. 3.

Fig. 3 is a sectional view taken on the line 3—3 of Figure 1, and

Fig. 4 is a sectional view taken on the line 4—4 of Fig. 2.

In the drawings 1 is a rectangular housing having an open front 2 and a cylindrical back wall 3 provided with a window 4 fitted with bars 5. There is a flange 6 projecting inwardly around the margin of the window. 7 is a revolute cylindrical member or casing open top and bottom and having substantially one-half of its wall closed as at 8, and having substantially one-half of its wall open as at 9. There is at each end of the revolute member an annular flange 10, and the flanges 10 are connected by flanges 11 arranged between the open and closed walls 8 and 9. The opening 9 may be fitted with a transparent sheet as of mica or the like 12 which may be removable. From the closed wall 8 at the top of the cylindrical member extends toward the center of the latter an arm 13 provided with a pivot 14. Depending from the top wall of the housing 1 there is a stirrup 15 fitted with bearings 16 and 17 for the pivot 14. There is a suspension bearing shown as of the antifriction or ball bearing variety and one of its elements 18 is fast on the pivot 14, and the other of its elements 19 is seated on the stirrup.

The pivot and axis of the cylindrical member are shown as arranged slightly out of vertical so that the flanges 10 on the cylindrical member by gravity are held up against the top and bottom flanges of the opening

4, thus insuring a good joint, and the flanges 11 make a good joint with the upright parts of the flange 6. Furthermore the cylindrical member can be very easily rotated as by means of the handle 20. The stud 21 to which the handle 20 is pivoted is arranged in line with a pair of stops 22 provided on the inner wall of the rectangular housing 1, so that the turning motion of the cylindrical member is properly limited in order to insure alignment of the upright parts of the flange 6 and of the flanges 11. The gas connection 23 is fixed to the bottom of the housing 1, whereas the electric light fitting 24 is merely placed in or taken out of the housing as may be required, and this can be done because it is supplied by a flexible cable 25. To facilitate this the front half 9 of the revolute cylindrical member or casing can be detached from the other half 8 of the casing by the joints which are provided between the lugs 26 on the detachable section and the notches on the projections 27 on the section of the casing which is fitted with the arm 13.

It will be obvious to those skilled in the art to which the invention relates that modifications may be made in details of construction and arrangement without departing from the spirit of the invention which is not limited to those matters or otherwise than as the prior art and the appended claims may require.

I claim:

1. An oven light comprising a housing having an open front and a cylindrical back wall provided with a window, a revolute cylindrical casing, a suspension pivot bearing interposed between the top of the housing and the top of the casing and constituting the sole support for the casing, said pivot bearing being arranged slightly out of vertical and concentrically with respect to the casing and eccentrically with respect to the cylindrical back wall to compel the cylindrical member by gravity to contact with the housing.

2. An oven light comprising a rectangular housing having an open front and a cylindrical back wall provided with a barred window there being a flange projecting inwardly around the margin of the window, a revolute cylindrical casing having a closed wall and an open wall there being a flange at the top and bottom of the casing and also two upright flanges for co-operation with the flange of the housing, an arm projecting

toward the center of the casing and provided with a pivot, and a stirrup antifriction bearing depending from the top of the housing for co-operation with the pivot to support the entire weight of the casing and to permit the flanges to contact by gravity.

3. An oven light comprising a housing having an open front and a cylindrical back wall provided with a window, a revolute

cylindrical casing having at its top an arm 10 and having an open bottom and including a section that is detachable, an electric lamp fitting removable upon the detachment of said section, and a suspension bearing interposed between the arm and the top of the 15 housing and arranged out of alignment with the axis of the casing.

CHAS. P. ROBSON.
